United States Patent Office

Des. 198,971
Patented Aug. 25, 1964

198,971

CHAIR

Herbert Ritts, 2221-51 Sepulveda Blvd.,
Los Angeles 64, Calif.

Filed July 25, 1963, Ser. No. 75,958

Term of patent 7 years

(Cl. D15—1)

Fig. 1

Fig. 2

The dominant features of my design reside in those portions shown in full lines on the drawing.

I claim:

The ornamental design for a chair, substantially as shown and described.
